EUGENE GLUCK, OF NEW YORK, N. Y.

WATCH-CRYSTAL-CUTTING MACHINE.

Application filed October 15, 1926. Serial No. 141,855.

This invention relates to devices for cutting sheet material to correspond to a given templet and more particularly is directed to a device for making watch crystals and other like purposes.

One object of the invention is to provide a device of the character described for cutting sheet material to form watch crystals of the proper size and shape, the bezel of the watch 10 being used as a templet or pattern. Not only circular or rectangular shaped watch crystals may be formed with said device but more particularly novel and odd shaped crystals, such as used for wrist-watches.

Another object of the invention is to provide a device of the character described having a pantographic adjustment whereby the blanks may be cut to form crystals of proper size to be held in the crystal retaining wall 20 of the bezel or somewhat larger than the bezel templet so as, for example, to provide sufficient material to permit convexing the watch crystal blank as will hereinafter appear.

A further object of the invention is to provide an improved device of the character described comprising few and simple parts forming a small compact apparatus, which shall be relatively cheap to manufacture, simple and easy to operate, and practical and efficient to a high degree in use.

Other objects of this invention will in part be obvious and in part hereinafter pointed out.

The invention accordingly consists in the 35 features of construction, combinations of elements, and arrangement of parts which will be exemplified in the construction hereinafter described, and of which the scope of application will be indicated in the following claims.

In the accompanying drawing, in which is shown one of the various possible illustrative 40 embodiments of this invention,

Fig. 1 is a plan view of a device embodying the invention, the wrist watch being shown 45 in dotted lines.

Fig. 2 is a front elevational view of the device in section, partly in elevation, and showing the interior construction.

Fig. 3 is a fragmentary cross-sectional view 50 showing the guide cooperating with the rim opening of the bezel.

Fig. 4 is a fragmentary cross-sectional view showing the cutter engaging the sheet material for forming the watch crystal.

Fig. 5 is a cross sectional view of a watch 55 case fitted with a convexly shaped crystal.

Referring in detail to the drawing, 10 denotes a device embodying the invention which is particularly adapted to cut sheet material in making crystals for wrist-watches. Said 60 device comprises a pair of gears 11 and 12 which may be interconnected to form a train by means of a worm 13. Said gear train may be mounted in any suitable manner, preferably being disposed in a horizontal 65 plane and housed in a casing 14.

The casing 14 is seen to comprise a base portion 14^a and a cover portion 14^b which completely enclose the gear train and provide bearings for the vertically extending 70 shafts 15 and 16 and a horizontally extending shaft 17 on which the gears 11 and 12 and worm 13, respectively, are mounted. The lower ends of the shafts 15 and 16 may be suitably journaled in the base portion 14^a 75 as at 14^c and 14^d, respectively, said shafts 15 and 16 projecting upwardly through the upper bearings 14^e and 14^f, respectively, formed in the cover portion 14^b. The shafts 15 and 16 may also be provided with shoulders 80 15^a and 16^a, respectively, on a mid-portion thereof, said shoulders preferably aligning with the downwardly facing surfaces of the bearings 14^e and 14^f, said shoulders and the downwardly facing side of the bearings serving as an abutment for the hubs 11^a and 12^a 85 of the gears 11 and 12, respectively, as is clearly shown in Fig. 2. The gears 11 and 12 may be firmly secured to the shafts 15 and 16, respectively, in any suitable manner as 90 by means of set-screws 18 and 19. The worm shaft 17 may be journaled in a removable sleeve bearing 32 secured to the casing cover 14^b by a screw 33, said shaft extending through the side of the casing and having a 95 crank handle 34 fixedly secured thereto for rotating the worm to actuate the gear train and operating the device 10, as will hereinafter more fully appear.

For retaining the casing portions 14^a and 14^b together, vertically extending through bolts 40 are provided. The lower ends of said bolts may serve as anchorages for suitable feet 41 as shown in Fig. 2.

The upper end of the shaft 15 extending 105 through the casing 14 has secured by a set-screw 20, suitable means 22 to rotate with said shaft for releasably securing a templet or pattern. In the form of the invention shown in the drawing a bezel 21^a of a watch 21 serves 110 as the templet, as will hereinafter more fully appear. Said templet securing means 22 may

consist of a chuck form of clamping mechanism which is seen to comprise a guiding bed 22^a on which is slidably mounted for movement to and from each other a pair of stepped jaws 22^b. A screw 22^a having the opposite ends thereof formed with left and right threads is provided to engage said jaws for adjusting same on turning either of knurled finger knobs 22^d mounted on the opposite ends 10 of said screw. By providing two knobs, at least one will always be conveniently positioned for adjusting the clamping mechanism 22. The two knobs also facilitate the application of a powerful tightening force to the 15 screw 22^a.

The stepped construction of jaws 22^b permit accommodating in said mechanism 22 watches of various thicknesses, said clamping mechanism 22 preferably being arranged so 20 that wrist watches are supplied with straps thereon which are not readily removable, such straps are not interfered with on rotation thereof on the device.

The upper end of the shaft 16 extending 25 through the casing has secured by a set-screw 23, suitable means 24 to rotate with said shaft for attaching a sheet of material or blank 25 from which the crystal 25^a is cut. Said sheet attaching means 24 is seen to comprise a disc 30 24^a which forms a rest on which the sheet 25 lies, the peripheral portion of said disc being threaded, as at 24^b, for engaging a threaded flange 24^c of an annular holder or clamping ring 24^d. (See Fig. 2.)

Extending upwardly from the center of the exterior side of the cover portion 14^b midway between said clamping mechanism 22 and the sheet attaching means 24 is a stanchion 26 through the center of which passes a bolt 27. Said bolt extends through an opening 28^a formed in a mid-portion of a horizontally extending double arm 28 pivotally supporting the latter for movement in a horizontal plane on said stanchion with one end portion 28^b 40 of said arm extending over the clamping mechanism 22, and the other end portion 28^c thereof extending over the sheet attaching means 24. A winged nut 27^a is provided on the upper end of the bolt 27 for retaining the arm 28 in position.

Supported on the arm end portion 28^b is a suitable guide 29 which preferably is made so as to be adjustable to and from the mechanism 22. Said guide may comprise a vertically disposed screw 29^a threaded into said arm end 28^b, the lower end 29^b being formed with a suitable point for engaging the rim of the watch bezel opening 21^b. The upper end of the screw may be made with a knurled head 29^c and a lock nut 29^d may be provided for retaining the screw in an adjusted position.

A suitable marker 30 is carried by the arm end portion 28^c. Said marker consists of a stylus or cutter 30^a which is adapted to be 65 pressed against the sheet material 25 on the

attaching means 24. To facilitate the removal and replacement of said cutter 30^a, the latter is fitted into a holder 30^b. Said holder may be made from a screw which is longitudinally slotted on the leading end 30^c thereof, 70 said end being counterbored along the axis thereof as at 30^d for receiving the end of the cutter 30^a. A knurled nut 30^e is provided for releasably clamping the cutter 30^a to the holder 30^b, as is clearly shown in Fig. 2. 75

A receptacle portion 30^f is provided on the arm end portion 28^c into which the holder 30^b extends and there is a suitable quick-detachable mounting for locking the holder in position. Said mounting may comprise a collar 30^g mounted for free movement on the head end of the holder 30^b, said collar having a projecting pin 30^h which forms a bayonet joint with a slot 30ⁱ formed in the receptacle portion 30^f. A compression spring 30^j is also 85 housed in said receptacle portion and is positioned between the nut 30^e of the holder and the collar 30^g so as to provide pressure for cutting the sheet material 25, as will be clearly understood from Fig. 2. 90

To make the guide 29 follow the contour of the rim opening 21^b of the watch bezel 21^a, a tension spring 31 is provided, one end of said spring being secured to a lug 28^d extending from the arm end 28^c and the other end thereof being anchored to a relatively fixed support, such as 26^a.

The operation of the device will now be clear. After the watch 21 for which a crystal is to be made is firmly secured to the clamping mechanism 22 with the bezel opening 21^b substantially in a horizontal plane and the sheet of material 25 from which the watch crystal is to be formed is fastened to the disc 24^a of the attaching means 24, the pointed end 29^b of the guide is adjusted to ride on the rim of the bezel opening 21^b. The holder 30^b is then locked in position so that the cutter 30^a presses against the sheet material 25. On the rotation of the crank handle 34 the gears 11 and 12 are revolved carrying the watch 21 and the sheet material 25, respectively, with them. The spring 31 retains the guide 29 against the rim of the bezel opening 21^b and the arm 28 is caused to swing to conform with the shape of the bezel opening 21^b directing the marker 30 to inscribe the shape of said opening on the sheet material 25, thus forming in outline the crystal 25^a. Inasmuch as the guide 29 which is associated with the support or holder 22 for the watch bezel has continuous and progressive engagement with the rim or crystal retaining wall on the bezel and controls the position of the cutter 30 associated with the holder 25 for the crystal blank, 110 the crystal which is marked or cut from the blank will conform to and fit snugly within said crystal retaining wall. 115

For the sheet material 25, any suitable substance may be used, such as celluloid or other 120

materials having like suitable properties. When celluloid is used, it is only necessary to scratch the shape thereon in outline in order to form the crystal 25^a since the outlined portion may be removed from the remaining sheet material by simply applying a separating force in the well understood manner.

Watch crystals preferably have convexed-ly, curved, cross-sectional shapes so as to 10 eliminate the possibility of the hands of the watch contacting therewith. To finish shaping the crystal, it may be given a permanent convexed cross-sectional shape in any well known manner as by pressing the crystal 25^a 15 under heat between molds (not shown) formed to the desired convexed shape. In that event, it is apparent that the size of the crystal 25^a must be necessarily larger than the size of the bezel opening 21^b in order to 20 provide the material to form the convexed shape of a finished watch crystal 25^b. To this end, the arm 28 is provided with a pantographic adjustment, the construction of which consists in making the opening 28^a in 25 the mid-portion of said arm 28 elongated and providing upper and lower shoes 35 on said arm through which extends the bolt 27. Said shoes clamp the arm 28 between them in adjusted position on tightening the winged nut 30 27^a so that the relative distances from the pivot point to the guide 29 and to the marker 30 may be varied. Thus, as seen from Fig. 2, by moving the arm to the right the arm end portion 28^c may be made relatively longer 35 than the arm end portion 28^b causing the marker 30 to outline the crystal 25^a relatively larger than the size of the bezel opening 21^b on operating the device 10.

Markings 36 on the side of the mid-portion 40 of the arm 28 and the lower shoe 35 may be provided for indicating the adjusted pivotal setting of said arm.

In the practical use of the device only a few sets of molds for forming the convexed cross-sectional shape on all sizes and shapes of 45 watch crystals are necessary if the approximate longest straight line distance across the bezel opening 21^b is known. To automatically determine said approximate distance, a ring 37 is mounted for rotation on the upper end of the stanchion 26 adjacent the arm 28. Said ring has an upwardly projecting portion 37^a for contact with lower shoe 35 so as to turn with the arm 28 in one direction. 50 Thus, as seen from Fig. 1, when the arm 28 is swung in counter-clockwise direction, the ring 37 is rotated, while when said arm is rotated clockwise the ring 37 is left unaffected. Therefore by providing markings 38 on said 55 ring and said stanchion 26, the maximum swing of the arm may be measured by reference to said markings 38, this measurement being proportional to the distance across the bezel opening. It is evident that it is a matter 60 of procedure whether the doming of the 65

crystals is done after they are cut. The term "blank" is used to denote a suitable piece from which the crystal is cut, and by "crystal" is meant the portion which is cut out, or outlined by scoring, in substantial conformity 70 with the bezel serving as a templet in which the crystal is to be inserted.

Cutting the crystal a trifle large is advantageous for insuring that the crystal will be held in the crystal retaining wall of the bezel, 75 which is, of course, slightly overhanging.

It should be noted that the novel features of the applicant's device may be incorporated in a less expensive construction than that shown in the drawing. Thus for example the 80 casing may be omitted and the clamping mechanism and the sheet material attachment means mounted directly on the gears.

It will thus be seen that there is provided 85 a device in which the several objects of this invention are achieved, and which is well adapted to meet the conditions of practical use.

As various possible embodiments might be 90 made of the above invention, and as various changes might be made in the embodiment above set forth, it is to be understood that all matter herein set forth or shown in the accompanying drawing is to be interpreted as 95 illustrative and not in a limiting sense.

Having thus described my invention, I claim as new and desire to secure by Letters Patent:—

1. A device of the character described comprising a plurality of gears, having a common driving means, means for securing a templet to move with one of said gears, means for supporting a sheet of material for movement with another of said gears, an arm guided by the templet for transcribing the shape of the latter to the sheet material on actuation of said gears, and a single worm positioned intermediate and directly engaging both said gears.

2. A device of the character described comprising a plurality of gears, having a common driving means, means for securing a templet to move with one of said gears, means for supporting a sheet of material for movement with another of said gears, an arm adapted to be guided by the templet for transcribing the shape of the latter to the sheet material on actuation of said gears, a pivot for said arm, said arm being adjustable in relation to the pivot to vary the relative size of the transcribed shape on the sheet material, and resilient means for urging pivotal movement of said arm and maintaining said arm in engagement with said templet.

3. A device of the character described comprising a plurality of gears, having a common driving means, adjustable means for securing templets of various sizes and shapes to move with one of said gears, means for sup-

porting a sheet of material for movement with another of said gears, an arm adapted to be guided by a templet mounted on said adjustable means, for transcribing the shape of the templet on the sheet material on actuation of said gears, a pivot for said arm and a spring for urging said arm about its pivot to maintain the same in contact with said templet.

4. A device of the character described comprising a casing, a pair of coplanar gears in said casing, a single drive means mounted between and directly engaging said gears, shafts for said gears extending through said casing, means carried on one of the gear-shafts for mounting a templet, means on the other gear-shaft for attaching a sheet of material, an arm pivotally mounted on the casing to extend over said means, guiding means at one end of said arm for engaging the templet, and marking means on the other end of said arm for inscribing the shape of the templet on the sheet material on actuation of said gears.

5. A device of the character described comprising a casing, a pair of gears in said casing, single drive means mounted intermediate and directly engaging said gears, shafts for said gears extending through said casing, means carried on one of the gear shafts for mounting a templet, means on the other gear shaft for attaching a sheet of material, an arm pivotally mounted on the casing intermediate the ends thereof to extend over said means, guiding means at one end of said arm for engaging the templet, and marking means on the other end of said arm for inscribing the shape of the templet on the sheet material on actuation of said gears, said arm being longitudinally adjustable along its pivot for varying the size of the inscribed shape on the sheet material.

6. A device of the character described comprising a casing, a pair of interconnected gears in said casing, shafts for said gears extending through said casing, a clamping mechanism carried on one of the gear-shafts for retaining an object having a flanged edge, said mechanism being adjustable for objects of various sizes, means on the other gear-shaft for attaching a sheet of material to be cut to conform to said flange, an arm pivotally mounted on the casing intermediate the ends thereof to extend over said attaching means, guiding means at one end of said arm for engaging said flange, means for retaining said guiding means normally in engagement with said flange, and marking means on the other end of said arm for inscribing the shape of the flange on the sheet of material on actuation of said gears.

7. A device of the character described comprising a casing, a pair of interconnected gears in said casing, shafts for said gears extending through said casing, means carried on one of the gear shafts for mounting a tem-

plet, means on the other gear shaft for attaching a sheet of material, an arm pivotally mounted on the casing intermediate the ends thereof to extend over said means, guiding means at one end of said arm for engaging the templet, marking means on the other end of said arm for inscribing the shape of the templet on the sheet material on actuation of said gears, and spring means acting on said arm urging the guiding means into cooperation with the templet.

8. A device of the character described comprising a casing, a pair of interconnected gears in said casing, shafts for said gears extending through said casing, means carried on one of the gear shafts for mounting a templet, means on the other gear shaft for attaching a sheet of material, an arm mounted on the casing intermediate the ends thereof to extend over said means, guiding means at one end of said arm for engaging the templet, marking means on the other end of said arm for inscribing the shape of the templet on the sheet material on actuation of said gears, and a spring having its respective ends secured to the casing and said arm for retaining the guiding means in effective cooperative position with the templet.

9. A watch crystal cutting device comprising means for supporting a crystal blank, means for supporting a watch bezel, and mechanism including a controlling guide having continuous and progressive engagement with the crystal retaining wall on the bezel for marking or cutting a crystal which will conform to and fit within said crystal retaining wall.

10. A watch crystal cutting device comprising a support for a crystal blank, a cutter associated therewith, a support for a watch bezel, a guide associated therewith for controlling the cutter, and mechanism for continuously and progressively causing said guide to engage the crystal retaining wall on the bezel and said cutter to cut or mark a crystal which will conform to and fit within the crystal retaining wall.

11. A watch crystal cutting device comprising a support for the crystal blank, a cutter associated therewith, a support for a watch bezel, a guide associated therewith, means for imparting synchronized movements to said supports, a device for connecting said guide and said cutter whereby the guide controls the position of the cutter, and means for causing the guide to continuously and progressively engage the crystal retaining wall on the bezel as the support for the bezel is moved, and said cutter to cut or mark a crystal as the support for the crystal is moved which crystal will conform to and fit within said crystal retaining wall.

12. A watch crystal cutting device comprising a support for the crystal blank, a cutter associated therewith, a support for a

watch bezel, a guide associated therewith, means for imparting synchronized movements to said supports, an arm pivotally mounted intermediate the ends thereof and supporting said guide and said cutter, whereby the movements of the cutter are controlled by the guide, and means for causing the guide to continuously and progressively engage the crystal retaining wall on the bezel as the support for the bezel is moved and said cutter to cut or mark a crystal as the support for the crystal blank is moved which crystal will conform to and fit within said crystal retaining wall.

13. A watch crystal cutting device comprising a support for the crystal blank, a cutter associated therewith, a support for a watch bezel, a guide associated therewith, means for rotating said supports in synchronism, a device for connecting said guide and said cutter whereby the guide and cutter are moved in synchronism toward and from the respective centers of rotation of said supports, and means for causing the guide to continuously and progressively engage the crystal retaining wall on the bezel as the support therefor is rotated and said cutter to cut or mark a crystal as the support for the crystal blank is rotated which crystal will conform to said crystal retaining wall.

14. A watch crystal cutting device comprising a support for the crystal blank, a

cutter associated therewith, a support for a watch bezel, a guide associated therewith, means for rotating said supports in synchronism, a pivoted arm device supporting said guide and said cutter whereby said guide and cutter will move in synchronism toward and from the respective centers of rotation of the supports, and means causing the guide to continuously and progressively engage the crystal retaining wall on the bezel as the support therefor is rotated and said cutter to cut or mark a crystal as the support therefor is rotated which crystal will conform to the crystal retaining wall.

15. A machine of the kind described comprising a watch-holder chuck, a support for a piece of sheet material from which to cut a crystal, means for rotating said chuck and support synchronously, a guide adapted to bear against the crystal retaining wall of the watch bezel, a tool to act on material on said support, a frame connecting said guide and tool to cause the tool to move toward and from the axis of rotation of said support in accordance with the lateral movements of the guide compelled by the rotating bezel, and means whereby said guide is yieldingly pressed laterally against the crystal retaining wall of the bezel.

In testimony whereof I affix my signature.

EUGENE GLUCK.
